US00D795295S

(12) **United States Design Patent** (10) **Patent No.:** **US D795,295 S**
Bull et al. (45) **Date of Patent:** **** Aug. 22, 2017**

(54) **DISPLAY SCREEN OR PORTION THEREOF
WITH GRAPHICAL USER INTERFACE**

(71) Applicant: **Apple Inc.**, Cupertino, CA (US)

(72) Inventors: **William E. Bull**, Campbell, CA (US);
Kourtny Hicks, Sunnyvale, CA (US);
Eric Hope, Duvall, WA (US);
Policarpo Wood, San Jose, CA (US)

(73) Assignee: **Apple Inc.**, Cupertino, CA (US)

(**) Term: **15 Years**

(21) Appl. No.: **29/582,837**

(22) Filed: **Oct. 31, 2016**

Related U.S. Application Data

(60) Continuation of application No. 29/525,138, filed on Apr. 24, 2015, now Pat. No. Des. 770,505, which is a continuation of application No. 29/352,674, filed on Dec. 23, 2009, now abandoned, which is a division of application No. 29/284,263, filed on Sep. 4, 2007, now Pat. No. Des. 607,033.

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The dashed broken lines in the FIGURE show a display screen or portion thereof, and form no part of the claimed design.

The dot-dash broken lines in the FIGURE and the area between the dot-dash broken lines and the dashed broken lines show portions of the graphical user interface that form no part of the claimed design.

1 Claim, 1 Drawing Sheet
